UNITED STATES PATENT OFFICE.

FRANK E. DODGE, OF NEW YORK, N. Y., AND FREDRICK H. RHODES, OF PHILADELPHIA, PENNSYLVANIA, ASSIGNORS TO THE BARRETT COMPANY, A CORPORATION OF NEW JERSEY.

METHOD FOR RECOVERING PYRIDINE BASES.

1,274,998.

Specification of Letters Patent.

Patented Aug. 6, 1918.

Application filed January 17, 1918. Serial No. 212,375.

To all whom it may concern:

Be it known that we, FRANK E. DODGE, of the city, county, and State of New York, and FREDRICK H. RHODES, of the city and county of Philadelphia, State of Pennsylvania, both citizens of the United States, have invented certain new and useful Improvements in Methods for Recovering Pyridine Bases, of which the following is a true and exact description, reference being had to the accompanying drawings, which form a part thereof.

Our invention relates to the recovery of the pyridine bases from the saturater bath liquor of the well known direct or semi-direct ammonium sulfate processes, and has for its object the economical recovery of the pyridine bases, and incidentally the purification of the bath liquor.

It is well known that in the manufacture of by-product coke and of illuminating gas some pyridine and pyridine homologues (as for example picoline, lutidine, quinoline, etc.,) are formed. A portion of these bases, especially those of the higher boiling points, condense in the hydraulic mains and primary coolers, and are thus contained in the tar. A considerable portion of the lower boiling pyridine bases is, however, not condensed with the tar, but comes through the primary coolers and tar extractors as a component of the gas.

In the direct ammonium sulfate process and in the semi-direct ammonium sulfate process the gas from the tar extractors is freed from ammonia by passing through a saturated solution of ammonium sulfate, which solution is kept acid with from ten to six per cent. of free sulfuric acid. The ammonia in the gas is absorbed by this acid solution and crystallizes out from the bath liquor as ammonium sulfate, which is removed and recovered. The pyridine vapor is also absorbed by the solution in the saturater bath, but only a negligible amount of pyridine or its compounds separates from the bath until the concentration of pyridine in the bath reaches a certain minimum value of approximately $2\frac{1}{2}$ per cent. The contamination of the ammonium sulfate by pyridine depends not only on the amount of pyridine in the bath, but also upon the care taken in washing the ammonium salts and with careful washing the bath may be per-

mitted to contain much more pyridine than $2\frac{1}{2}$ per cent, without loss of pyridine with the salt.

In our process we remove the bath liquor from a saturater bath which has been in use, preferably before the saturation of the bath liquor with pyridine bases has reached the point where the ammonium sulfate is contaminated by pyridine sulfates. We then pass ammonia or ammonia vapor into the bath, with the result that the ammonia first reacts with the free acid present to form ammonium sulfate. After most of the free acid is thus neutralized, the ammonia begins to react with the pyridine sulfate in the solution, forming ammonium sulfate, and setting free the pyridine bases. By saturating the bath solution with ammonia in this way, it is, we have found, possible to liberate all of the pyridine bases in the bath liquor.

Having freed the pyridine bases in the bath liquor from their combination with sulfuric acid as above described, we next proceed to recover the pyridine bases from the solution, and by preference we accomplish this by distilling the solution until no more of the pyridine bases come over with the distillate. The heat necessary for this distillation may be furnished by the heat of the reaction of the ammonia with the free acid and pyridine sulfate in the solution, but it is preferable to supplement this with heat from some outside source.

The pyridine in the distillate from the neutralizing still may be separated from the water with which it passes from the still by any of the well known methods, as for example by agitating the condensed distillates with an oil. By preference, however, we accomplish the separation of the pyridine bases from the water of the distillate by saturating the distillate with ammonia gas, which causes the pyridine bases to separate as a distinct layer, superimposed on the layer of water, owing to which gravitational separation the water and the pyridine bases can be readily drawn off into separate tanks.

It is preferable, but not essential, that the ammonia or ammonia vapor which is caused to pass through the bath liquor in the neutralizing still should be partially dried by passing it through a separator before it is admitted to the neutralizing still.

- We would also note that in place of using ammonia vapor or ammonia in the neutralizing still, it is possible to use an aqueous solution of ammonia to neutralize all or a portion of the free acid and of the pyridine sulfate. For example, the aqueous solution of ammonia which is obtained when the distillate is saturated with ammonia gas may be used for this purpose.
- 10 We would also note here that an alternative method of recovering the pyridine bases from the neutralized bath liquor containing the pyridine bases freed from combination with the sulfuric acid is to agitate the neutralized solution of the bath with an oil which will take up the pyridine bases. The oil layer is then separated from the bath and the pyridine bases recovered from it by a suitable means, as for example by agitation with an acid. This particular modification of our process forms the subject matter of our co-pending application for Letters Patent filed Jan. 17, 1918, Serial Number 212,376.
- 15 Our invention in its detail will be best understood as described in connection with the apparatus which we have devised for its most efficient practice, and which is shown in the diagrammatic drawing forming part 20 of this application, in which
- A indicates a storage tank for the bath liquor drawn from the saturator. B is the neutralizing still, which should be lead-lined and into which proper quantities of the old bath liquor is forced from the tank A through the pipe C. O is a lead steam coil contained in the still, and used for raising the temperature of the bath when necessary. N is a pipe leading from an ammonia still 25 and as shown, leading into the heater and separator M, which is formed with a partition M' and a steam coil M² for raising its temperature, M³ indicating a drain pipe. The dried ammonia passes from the heater and separator through the pipe N' to the still, and enters the bath through the cracker pipe indicated at N². The still B can be drained through the pipe K, having the valve k, and leading as shown to a filter 30 L, from which the liquor passes through the pipe K' to the storage tank K². P indicates an acid inlet pipe leading into the still B. D is a conduit through which the distillates escape from the still B, and which 35 terminates in a worm condenser D' located in the condenser tank E and connecting with the pipe D², in which is preferably situated a sight glass D³ having a vent D⁴, and which connects through the pipes D⁵ and D⁶, 40 each provided with valves d and d', with the receiver tanks E and E'. These tanks are drained at suitable times through the pipes F and F', provided with valves x and x', into the pipe G, which pipe in turn connects 45 through the pipe G' with the pyridine stor-
- age tank H, and through pipe G² with the pipe G³ leading to the tank A, and with the pipe G⁴ which may lead to a hot drain tank not shown. g', g², g³ and g⁴ are valves by which the course of the liquid through and from the pipe G and its connections may be regulated at will. I is a pipe leading from a still or other source of ammonia vapor, and connecting through the pipes I' and I² with the receiver tanks E and E', i' and i² indicating valves. J and J' are vents for the ammonia vapor, which of course will be connected with some receptacle for the ammonia.
- 50 In operation, the bath liquor is pumped from the tank A into the neutralizing still B, and ammonia, preferably dried in the heater and separator M, is passed through the pipes N and N' into the bath, with the result of neutralizing the acid of the bath and decomposing the pyridine sulfates. The admission of ammonia is continued until all of the pyridine sulfates are decomposed, and the heat of the reaction, supplemented, if necessary, by extraneous heat, drives off the freed pyridine bases in admixture with watery vapor through the pipe D, the distillate being condensed in the condenser D' and E, and the condensed water and pyridine bases being delivered into the tanks E and E' at the will of the operator. Ammonia vapor is then delivered to the receivers E and E' through the pipes I' and I², with the result that the pyridine bases separate gravitally from the water and the contents of the receivers is then drawn off, the water charged with ammonia being delivered to the tank A or through the pipe G to a hot drain tank not shown, and the pyridine bases being delivered to the tank H.
- 55 The apparatus above described forms the subject matter of our co-pending application for Letters Patent filed January 27, 1918, Serial Number 212,377.
- Having now described our invention, what we claim as new and desire to secure by Letters Patent, is:
1. The method of separating the pyridine bases from the saturator baths of the direct or semidirect ammonium sulfate processes, which consists in saturating the bath liquor, consisting of a saturated acid solution of ammonium sulfate contaminated with salts of pyridine, with ammonia to liberate the pyridine bases from their combination with the acid of the bath and recovering the freed pyridine bases from the neutralized bath.
  2. The method of separating the pyridine bases from the saturator bath of the direct or semi-direct ammonium sulfate processes, which consists in saturating the bath liquor, consisting of a saturated acid solution of ammonium sulfate contaminated with salts of pyridine, with ammonia to liberate the

pyridine bases from their combination with the acid of the bath and separating the free pyridine bases from the neutralized bath by distillation.

5 3. The method of separating the pyridine bases from the saturator baths of the direct or semi-direct ammonium sulfate processes, which consists in saturating the bath liquor, consisting of a saturated acid solution of

10 ammonium sulfate contaminated with salts

of pyridine, with ammonia to liberate the pyridine bases from their combination with the acid of the bath, separating the freed pyridine bases from the neutralized bath by distillation, and treating the condensed distillate with ammonia to effect a gravital separation of the pyridine bases from the condensed liquid. 15
